UNITED STATES PATENT OFFICE.

RUSSEL G. WOODWARD, OF WAUKEGAN, ILLINOIS, ASSIGNOR TO THE UNION SPECIAL SEWING MACHINE CO., OF CHICAGO, ILLINOIS, A CORPORATION OF ILLINOIS.

PRESSER-FOOT FOR SEWING-MACHINES.

No. 821,773.

Specification of Letters Patent.

Patented May 29, 1906.

Application filed April 8, 1901. Serial No. 54,898.

To all whom it may concern:

Be it known that I, RUSSEL G. WOODWARD, a citizen of the United States, residing at Waukegan, in the county of Lake, State of Illinois, have invented certain new and useful Improvements in Presser-Feet for Sewing-Machines, of which the following is a description, reference being had to the accompanying drawings and to the letters of reference marked thereon.

My invention relates to an improvement in presser-feet for sewing-machines, the object being to provide a presser-foot for use on a machine for box-plaiting, which is the invention of Chester McNeil and myself and is disclosed in an application filed in the United States Patent Office on the 16th day of April, 1901, Serial No. 56,063.

The invention consists of a presser-foot adapted to coöperate with complementary devices to raise a series of parallel tucks on the face of a fabric and in the further operation of the machine to flatten out the tucks either in opposite directions to form a box-plait or in the same direction to lay the tucks in series.

The invention is illustrated in the accompanying drawings, in which—

Figure 1 is a perspective view of a presser-foot embodying my invention. Fig. 2 is a bottom plan view of the same. Fig. 3 is a sectional view. Fig. 4 is a top plan view, and Fig. 5 is a perspective view illustrating the relation of the plates or fins on the throat-plate.

In the drawings, A represents the presser-foot, having the usual needle-openings a a, herein shown as arranged for the passage of two sets of needles set oblique to each other respecting the line of feed. It has two slots or grooves b b on its under side adapted to coöperate with plates or fins f f on the throat-plate B to form tucks or ridges on the material. This throat-plate has needle-openings e and also openings for the passage of the feed-dog. The looper mechanism is shown at d. A tongue c extends from the forward end of the presser-foot in line between the slots b, which travels between the tucks. As herein shown in rear of the needle-openings, the foot is cut away upon opposite sides, as at d d, and beveled down to a sharp edge, leaving an open space between the end of the slots b b and the sharp edge. As the goods

after being sewed pass out of the slots in raised position the sharp edges of the presser-foot openings d d act to iron down the tucks or ridges, turning them in opposite directions, leaving a box-plait; but it will be understood that I do not wish to be limited to this arrangement. These slots b b extend into the needle-openings and also back of the same, terminating in the openings d d. If they terminated at the needle-openings, the plait would be crushed down vertically by the portion of the presser-foot between the needle-openings and the openings d d.

Having thus described my invention, what I claim, and desire to secure by Letters Patent, is—

1. A presser-foot for sewing-machines having slots on its under side to coöperate in forming and guiding tucks on the face of a fabric, and having cut-away portions so arranged with relation to the slots that the sides of said cut-away portions will flatten out said tucks; substantially as described.

2. A presser-foot for sewing-machines having slots on its under side to coöperate in forming and guiding tucks on the face of a fabric, and having in rear thereof cut-away portions, so arranged with relation to the slots that the sides of said cut-away portions will flatten out said tucks; substantially as described.

3. A presser-foot for sewing-machines having slots on its under side coöoperating to form and guide tucks on the face of the fabric, with openings d, d, in rear thereof said openings having walls to guide and deflect the tucks; substantially as described.

4. A presser-foot for sewing-machines having slots on its under side coöoperating to form and guide tucks on the face of the fabric, with openings d, d, in rear thereof, said presser-foot being provided with a forwardly-projecting tongue, c; substantially as described.

5. A presser-foot for sewing-machines, having a plurality of needle-openings, and having also slots coöoperating to form and guide tucks on the face of the fabric, and opening into said needle-openings, with means on said presser-foot in rear of the needle-openings to guide and deflect said tucks, substantially as described.

6. A presser-foot for sewing-machines, hav-

- ing a plurality of needle-openings arranged in a plane oblique to each other respecting the longitudinal axis of a presser-foot, said presser-foot having a plurality of slots coöperating to form and guide tucks on the face of the fabric, and opening into the needle-openings, with means on said presser-foot in rear of the needle-openings to guide and deflect said tucks; substantially as described.
10. 7. A presser-foot for sewing-machines, having suitable needle-openings arranged in a line oblique to the longitudinal axis of the presser-foot, and having a plurality of slots coöperating to form and guide tucks on the face of the fabric, said presser-foot having cut-away portions upon opposite sides of a center line, in rear of said needle-opening; substantially as described.
8. A presser-foot for sewing-machines, having suitable needle-openings arranged in a line oblique to the longitudinal axis of the presser-foot, and having guiding-slots extending into the needle-openings, and having cut-away portions arranged obliquely to each other; substantially as described.
9. A presser-foot for sewing-machines having a suitable needle-opening and guiding-slot in advance of the needle-opening, and another guiding-slot in rear thereof, terminating in a cut-out portion the walls of said cut-out portion bearing on the material to flatten out the tucks formed therein; substantially as described.
10. A presser-foot having means to guide a vertical tuck to the needle-opening and deflect it to lie in a horizontal plane in rear of said opening; substantially as described. 35
11. A presser-foot having a plurality of vertical slots to guide vertical tucks to a plurality of needle-openings and a plurality of deflecting-surfaces to deflect the upright or vertical tucks to lie in a horizontal plane; substantially as described. 40
12. A presser-foot for sewing-machines having slots on its under side to coöperate in forming and guiding tucks on the face of the fabric, and provided with suitable needle-openings in which the slots terminate, said presser-foot having cut-away portions in rear of the said needle-openings and slots between 50 said needle-openings and the cut-away portions, the sides of said cut-away portions being so formed as to flatten out said tucks; substantially as described.

In testimony whereof I affix my signature 55
in presence of two witnesses.

RUSSEL G. WOODWARD.
